US00D804518S

(12) **United States Design Patent** (10) Patent No.: **US D804,518 S**
Motenko et al. (45) Date of Patent: ** Dec. 5, 2017

(54) **DISPLAY SCREEN PORTION WITH
GRAPHICAL USER INTERFACE**

(71) Applicant: **Stacked Restaurants, LLC**, Yorba Linda, CA (US)

(72) Inventors: **Paul Motenko**, Mission Viejo, CA (US); **Jeremiah Hennessy**, Yorba Linda, CA (US); **Brian Pearson**, Santa Ana, CA (US); **Nanette McWhertor**, Costa Mesa, CA (US); **Jordan Mozer**, Chicago, IL (US); **Jeff Carloss**, Naperville, IL (US); **Camille Mankus**, Chicago, IL (US); **Rick Valicenti**, Chicago, IL (US); **Bud Rodecker**, Chicago, IL (US); **John Pobojewski**, Elgin, IL (US)

(**) Term: **15 Years**

(21) Appl. No.: **29/541,265**

(22) Filed: **Oct. 1, 2015**

Related U.S. Application Data

(62) Division of application No. 29/423,172, filed on May 29, 2012, now Pat. No. Des. 742,899.
